UNITED STATES PATENT OFFICE.

PETER A. JOHANSEN, OF OMAHA, NEBRASKA.

GAS-RANGE LIGHTER.

No. 894,954.

Specification of Letters Patent.

Patented Aug. 4, 1908.

Application filed December 6, 1907. Serial No. 405,304.

To all whom it may concern:

Be it known that I, PETER A. JOHANSEN, a citizen of the United States, residing at Omaha, in the county of Douglas and State of Nebraska, have invented certain new and useful Improvements in Gas-Range Lighters, of which the following is a specification.

This invention has reference to automatic means for lighting gas ranges electrically, at 10 the time of turning on the gas.

The object of the invention is to provide an inexpensive device, operated by electricity, which may be attached to any ordinary gas range, and by means of which the burner 15 of the range may be automatically lighted, which will consist of few parts and will be reliable in operation.

Another object is the provision of devices which, when operated, will cause the flame 20 to be thrown a considerable distance, comparatively, from the igniting devices, for lighting the burner, for the purpose of preventing decarbonization of parts.

Another object is the provision of devices 25 for causing the ignition flame to be thrown upon the same horizontal plane as that of the burner; and a further object is the provision of ignition devices which are located out of the pathway of the igniting flame, to prevent 30 decarbonization, and the use of devices for automatically lighting the gas range, which may be inexpensively replaced when worn or injured.

The invention consists of the combination 35 and arrangement of parts herein described, pointed out by the claims and illustrated by the drawing, wherein,—

Figure 1 is a plan view of the invention, the gas burner of the range being partly 40 broken away. Fig. 2 is a vertical, side view of the parts shown in Fig. 1. Fig. 3 is an enlarged detail, being a plan view of sparking devices employed at the terminal of the discharge pipe. Fig. 4 is an enlarged sectional 45 view of the nozzle or terminal of the discharge pipe.

Referring now to the drawing for a more particular description, numeral 1 indicates the gas storage pipe and 2 the pilot or supply 50 pipe of a gas range, the gas burner being indicated at 3, and for purposes of the invention I employ the pipe-section 4, which has threaded end connections 5 and 6 with, respectively, pipes 1 and 2, so that the device 55 may be conveniently placed in operative position upon a gas range. Section 4, which

may be of any required length or size, is provided with the valve housing 7, and gas-cock 8 when placed therein may be rotated by means of handle 9. As thus constructed, 60 pipes 1 and 2 and valve section 4 are disposed upon the same horizontal plane, burner 3 being disposed above this plane. I construct the discharge-pipe 10, comprising a body-portion 11 extended in the direction 65 of burner 3, parallel with supply-pipe 2, said discharge-pipe being connected to pipe-section 4 by the transverse portion 12. A portion 13 of the discharge-pipe is disposed above the plane of supply-pipe 2, and is disposed, substantially, upon the same plane as 70 the upper surface of burner 3, said portion 13 being connected by means of the curved portion 14 with portion 11 of the discharge-pipe.

I provide the valve-housing 15 for discharge-pipe 10, gas-cock 16 being seated therein, and as thus described the discharge-pipe is disposed adjacent supply-pipe 2 a convenient distance for mounting thereon devices presently to be explained; and transverse portion 12 may be disposed closely adjacent pipe 1, as shown, that there may be adequate space for operatively securing upon the terminal of the discharge-pipe certain 80 sparking devices, without encroaching upon 85 the space occupied by the burner; and as thus constructed nozzle or terminal 17 of the discharge-pipe is disposed upon the horizontal plane of the burner.

Rigidly upon the upper end of gas cock 8 90 is mounted pinion 18, and upon the upper end of gas cock 16, and in gear with pinion 18, is secured pinion 19. Mounted rigidly upon gas-cock 16, and having a center coincident therewith, is barrel or cylinder 20; 95 and upon portion 13 of the discharge pipe is mounted guide 21, within which is seated shaft or sparking-rod 22 having a transversely formed arm 23 upon its free end, the opposite end of this rod having a pivotal 100 mounting as at 24 upon the face and near the outer wall of cylinder 20. It will be understood that a swinging movement of handle 9 in the direction indicated by its arrow, will cause a corresponding rotatable movement 105 of pinion 18 to cause a revolute movement of pinion 19 in the direction of its arrow, thereby causing rod 22 to have a limited rearward movement, said movement of the handle also causing a revolute movement 110 of both gas-cocks.

Near the free end of portion 13 of the dis-

- charge pipe is seated insulating-ring 25, and secured thereon is the metal ring 26, and upon this metal ring is mounted the metal post 27 which extends outwardly somewhat further than nozzle 17, and upon post 27 is secured the metal finger 28, preferably bent to form the transverse contact-blade 29; and as thus described, contact-blade 29 has a stationary insulated mounting upon and is disposed adjacent the terminal of the discharge-pipe. Contact-blade 29 may be constructed of any resilient metal and is disposed in the path traversed by contact-arm 23 during the lengthwise movement of rod 22 so that a contact of these metal parts will be made when rod 22 is actuated by the revolute movement of pinion 19.
- Handle 9 is secured upon gas-cock 8 so that it occupies a position at a right angle to supply-pipe 2 and to valve-section 4 at the time this valve is closed, and at this time the parts are in the position shown in Fig. 1, contact-blade 29 being disposed between arm 23 and the end of nozzle 17, and at this time valve or gas cock 16 is closed.
- By manually swinging handle 9 in the direction of its arrow 90 degrees, gas-cock 8 will be open, and this movement will actuate pinion 19 and, thereby, open valve 16 to allow gas to pass through the discharge pipe and nozzle 17; at the time of this movement arm 23 will make contact with and will pass blade 29 since sparking-rod 22 will have a rearward movement. Any electrical means is employed, as battery 30, to energize wires 31 and 32, and spark-coil 33 is employed; wire 31 may have a metallic connection as at 34 upon the valve-housing 15 so that arm 23 of rod 22 will be energized with electricity of one sign, and wire 32 will energize blade 29 with electricity of the opposite sign, and at the time gas is passing nozzle 17, a spark is created by arm 23 "tripping" upon blade 29, already explained, which ignites burner 3.
- It will be noted that the metal parts which coöperate to produce the spark are located at a considerable distance from burner 3 and this is desired so that decarbonization of these parts may be prevented. Cooking vessels, when placed upon the burner, cause the burning gas to flare outwardly from the burner, and in order that the metal devices may not be injured by the heat, they are disposed as shown, and an ignition flame is thrown, in the present instance, from a safe distance upon the plane of the burner, and these devices and their arrangement will now be explained.
- Nozzle 17 is provided with an orifice 35 of less diameter than any part of the bore 36 of the discharge pipe, and on this account, at the time of opening the valves as described, gas is driven from the nozzle with considerable force at the time the spark is created, so that a flame of adequate length passes from the nozzle to reach and to reliably ignite the gas of the burner. It will be noted that arm 23 and blade 29 are located near, but not at the front of orifice 32, and thereby these parts are not obtrusive to prevent a free flow of the gas at the time the latter is forced out of the orifice; also the possibility of decarbonization of these metal parts is minimized by reason of this location since they are not in the pathway of the forwardly forced stream of flame coming from the nozzle when the valves are open.
- It will be understood by those conversant with the operation of gas cocks, that gas will pass before the valve has rotated the entire 90 degrees, and in the present instance gas reaches burner 3 before handle 9 has been rotated the 90 degrees mentioned. Since pinion 19 upon the discharge pipe has a less diameter than pinion 18, its revolute movement, when actuated, is greater than that of pinion 18; gas-cock 16, therefore, during operation, rotates more rapid and allows passage of gas sooner than does gas-cock 8. It will be understood, therefore, that gas will pass the discharge-pipe before handle 9 has moved the full 90 degrees; during this movement contact-arm 23 engages blade 29 and bends the latter inwardly, since rod 22 has a lengthwise movement from the partial rotation of cylinder 20; as soon, however, as blade 29 is "tripped" or released from arm 23 the spark is made, and at this moment gas has passed both valves, so that the burner is lighted; when the handle has been moved 90 degrees, as described, gas is freely communicated to the burner through the supply-pipe, but at this time valve 16 of the discharge-pipe is closed, this closure being effected by reason of the difference in diameters mentioned of pinions 18 and 19.
- Pinion 18 is provided with blanks 37 and 38 upon its periphery which operate as stop-lugs to contact with the teeth of pinion 19, to limit the movement of the gas-cocks and handle 9, and thereby prevent the turning on of gas by use of the handle except in the manner described.
- If, for any reason, blade 29 or arm 23 should become injured or worn, they may be replaced at slight expense, as they are separate parts and are conveniently mounted in a manner to be readily removed or replaced.
- Having fully described my invention, what I claim as new and desire to secure by Letters Patent is,—
1. In a lighter for gas range burners, the combination with a gas supply-pipe having a gas-cock with a pinion thereon, of a discharge pipe in communication with said supply-pipe and having a gas-cock with a pinion registering with the pinion of the supply-pipe gas-cock; an insulated metal contact-blade energized by electricity of one sign and in

electrical communication with a spark-coil and disposed adjacent the terminal of the discharge-pipe; a metal sparking-rod energized by electricity of an opposite sign and having a terminal adjacent said insulated metal contact-blade, its opposite end having a mounting upon the gas-cock of the discharge-pipe; said pinions upon the gas-cocks of the supply-pipe and discharge-pipe being movable when rotating the gas-cock of the supply-pipe to cause a rearward movement of the terminal of the sparking-rod contactingly with and passing said insulated metal contact-blade.

2. In combination, a lighter for gas ranges, comprising a discharge-pipe having a contracted orifice and provided with a gas-cock with a gear thereon, a sparking-rod disposed longitudinally of the discharge-pipe and having a transversely-formed contact-arm disposed adjacent said contracted orifice, its opposite end having a mounting upon the gas-cock of said discharge-pipe; a gas supply-pipe having a gas-cock with a gear mounted thereon to register with the gear of the discharge-pipe gas-cock; an electrical connection between the contact-arm of said sparking-rod and said metal contact-blade; the

gear of the gas-cock of said supply-pipe being revoluble to cause a rotatable movement of the gas-cocks of the supply-pipe and discharge-pipe, and to cause the contact-arm of said sparking-rod to traverse, contactingly, said metal contact-blade.

3. In combination, an electrical gas range lighter, comprising a gas-supply pipe, a battery, a spark coil, a gas discharge pipe; a first metal friction member having a connection with the spark-coil and with one of the poles of the battery; a second metal friction member having a connection with the opposite pole of the battery; a first gas-cock mounted upon the gas supply-pipe; a second gas-cock mounted upon the discharge-pipe; a gear connection between said first gas-cock and said second gas-cock to cause a contact of said first and second metal friction members, and to cause a revoluble movement of said first and second gas-cocks.

In testimony whereof I have affixed my signature in presence of two witnesses.
